UNITED STATES PATENT OFFICE.

ALBERT SCHMID, OF ALLEGHENY, PENNSYLVANIA.

DESIGN FOR AN OIL-BOX.

SPECIFICATION forming part of Design No. 20,481, dated January 13, 1891.

Application filed December 13, 1890. Serial No. 374,644. Term of patent 14 years.

To all whom it may concern:

Be it known that I, ALBERT SCHMID, a citizen of the United States, residing in the city of Allegheny, in the county of Allegheny and State of Pennsylvania, have invented and produced a new and original Design for Oil-Boxes for Electric Street-Car Motors, of which the following is a specification.

The design is illustrated in the accompanying drawing.

The figure is a perspective view showing the general form of oil-box.

The principal features of the design of the box consist in the general ovate or pear-shaped form, being rounded at one end C into approximately the arc of a circle and narrow-

ing gradually toward the other end D. The thickness of the box is approximately the same throughout. The box thus fashioned presents a pleasing appearance and is at the same time well suited to its use.

I claim as my invention—

The design for oil-boxes for electric street-car motors, substantially as herein shown and described.

In testimony whereof I have hereunto subscribed my name this 8th day of December, A. D. 1890.

ALBERT SCHMID.
